DISCHARGE DEVICE FOR USE WITH
CONVEYERS

George Thompson Smith, Loughborough, England, assignor to Herbert Morris Limited, Loughborough, England

Application November 28, 1934, Serial No. 755,129
In Great Britain February 17, 1934

12 Claims. (Cl. 214—61)

This invention relates to improvements in conveyor systems and particularly to discharge devices therefor whereby the load carriers, such as trays, boxes, trip hooks, are adapted to discharge their loads at any one of a series of discharge stations along the conveyer track.

In accordance with a principal object of the present invention means are provided to operate a tilting mechanism whereby each load carrier is adapted to discharge its load at any predetermined station.

A further object is to provide means whereby once a load carrier has discharged its load the tilting mechanism is not operated when passing succeeding stations.

Another object is to provide for setting the discharge mechanism by means of a remote control device whereby the load carried by any particular load carrier is discharged at any predetermined station, while in accordance with a still further object of the invention a signalling device is incorporated whereby warning is given of an approach of a loaded carrier to any particular station or the approach of a carrier which has discharged its load.

The invention is illustrated in the accompanying drawings in which Fig. 1 is a side elevation of the discharging device of the present invention applied to an overhead chain driven trolley type conveyer, Fig. 2 being an end view thereof, Fig. 3 is a section to a larger scale through the operating mechanism for the discharge of a load, Fig. 4 is a section on the line A—A of Fig. 3, while Fig. 5 is a diagrammatic elevation showing a setting arrangement for the discharge mechanism. Fig. 6 is an end view looking in the direction of the arrow A (Fig. 7) showing a ratchet mechanism providing an alternative setting arrangement for the discharge mechanism and also a switch operating mechanism of a signalling device for use with the conveyer, Fig. 7 is a cross-section thereof looking in the direction of the arrow B. Fig. 8 is an elevation showing a part of the conveyer system and including a ramp for operating the ratchet mechanism. Fig. 9 is an elevation of the ramp looked at in the direction of the arrow C—C of Fig. 10. Fig. 10 is an end elevation of the conveyer system shown in Fig. 8. Fig. 11 shows the ramp mechanism for setting the ramp looked at in the direction of the arrows D—D (Fig. 10), while Fig. 12 is a detail to enlarged scale showing the switching mechanism for the signalling device.

Referring to the drawings, 1 denotes the overhead runway which is provided with a number

of spaced trolleys 2 which support the driving chain 3 and the trays 4 (only one trolley and one tray being shown). The trays 4 are pivotally mounted on U-shaped frames 5 carried by side plates 6 attached to the trolleys 2. The arrow T indicates the direction of travel of the trays 4.

Mounted in the side plates 6 is a spindle 7 on which is mounted a ratchet wheel 8 co-operating with a spring-pressed pawl 9 mounted on a bifurcated arm 10 which is adapted to be rocked on the spindle 7. A setting dial 11 mounted on the spindle 7 serves for setting the ratchet wheel 8 in any desired position, a spring pressed ball catch 12 engageable with recesses on the face of the ratchet wheel 8 acting to hold it in any set position.

The ratchet wheel 8 is provided with teeth 13 corresponding in number to the discharge stations to be served by the conveyer, one tooth 13a being specially shaped (e. g. cut deeper) so that the pawl 9, when engaging this tooth, is also permitted to engage a tooth 14 on a segmental lever 15 mounted on the spindle 7. The lever 15 is connected by means of links 16, 17, and 18 in the usual manner to one end of a bell crank lever 19 pivoted at 20 to the frame 5 of the tray 4 and attached at the other end to the tray 4 which is pivotally mounted in the support 5. The link 17 is pivoted on a shaft 21 supported by a bracket 22.

The bifurcated rocking arm 10 terminates at one end in a pair of arms 23 supporting a spindle 24 on which are mounted rollers 25 adapted to engage with stationary ramps 26 (of which only one is shown) at each discharge station. The arm 10 is provided at its other end with a balance weight 27 serving to return the arm to normal position when released by the ramp 26.

Steadying rolls 28 supported in a bracket 29 serve to prevent the tray 4 from swinging when the rollers 25 engage the ramps 26 as shown in dotted lines. The steadyng rolls 28 are so positioned that they are just clear of the horizontal portion of the ramp 26 when the rollers 25 engage the inclined portion of the ramp 26. A bracket 29 attached to the side plates 6 by means of a clamping plate 31 also acts as a stop for the link 17 of the tray tilting mechanism.

In operation, if the tray 4 is to discharge its load at say the third station, the setting dial 11, and thus the ratchet wheel 8, is adjusted so that at such third station the rocking arm 10 actuated by the ramp 26 at this station will cause the spring-pressed pawl 9 to engage the shaped tooth 13a and the tooth 14 of the segmental lever 15.

which will thus be rocked about the spindle 7 to operate the connecting links 16, 17, and 18 and tilt the tray 4 about its pivot to discharge the load. The lever 15 is returned to normal position by means of a stop 30 on the arm 18.

The tooth 13 on the ratchet wheel 8 succeeding the shaped tooth 13a is spaced from the next tooth 13b by an amount greater than the travel of the pawl so that once the load has been discharged from the tray 4 and the ratchet 8 has been advanced one tooth, the pawl 9 engages with this longer tooth 13b and merely rides backwards and forwards. Consequently at all succeeding stations the ratchet wheel 8 is not advanced.

The side plates 6 are preferably pivoted to the trolleys 2 so that the trays 4 can remain in a horizontal position when the runway 1 is inclined.

If desired, the ratchet wheel 8 may be remotely controlled in which case the spindle 7 is extended and is provided with a star wheel engaged by a rack or alternatively by a ratchet wheel engaged by a pawl operated by a succession of ramps which causes the ratchet wheel and setting device to rotate until the desired setting is obtained. If it is desired that the ratchet should have the same setting for all the trays or the like an ordinary rack with fixed teeth may be used for rotating the star wheel.

In one embodiment suitable for use in varying the setting for different trays the rack teeth are constituted as shown in Fig. 5 by separate teeth in the form of a series of pins 32 mounted in a fixed frame 33, the pins being normally held out of engagement with a star wheel 34 provided on an extension of the spindle 7 by means of springs 35. By means of a sliding ramp 36 actuated by a pinion 37 adapted to engage the remote ends of the pins 32, any one or more of the pins may be depressed against the action of the springs 35 to engage and rotate the star wheel 34 and thus the ratchet wheel 8 by an amount dependent on the number of pins 32 depressed.

Referring now to the arrangement shown in Figs. 6 to 11 the spindle 7 carrying the ratchet 8 is extended to carry a ratchet wheel 38 which is engaged by a pawl 39. The pawl 39 is mounted at one end of a link 40 pivotally mounted on a spring-controlled lever 41 and a lever 41a, the end 41b of which co-operates with a stop 41c. The link 40 carries at its other end a forked member 42 supporting a roller 43.

To provide for any desired setting of the ratchet wheel 8 a ramp 44 is disposed in the path of a tray so that it engages the roller 43, the ramp 44 being suitably mounted to provide for vertical movement so as to move it clear of the roller 43 and provided with means to vary the number of teeth 45 engaged by the roller 43.

The number of teeth engageable by the roller 43 is varied by rendering certain of the teeth ineffective by means of a rack 46 which is moved longitudinally by means of a pinion 47. The pinion 47 is mounted on a spindle 48 which carries at its other end a pinion 49 meshing with a toothed sector 50 mounted on a spindle 51. The spindle 51 and sector 50 are rotated by means of a handle 52 rotating a sprocket wheel 53 mounted on a spindle 54, an endless chain 55 passing over a further sprocket wheel 56 mounted on the spindle 51. The handle 52 is moved over a graduated dial 57 which indicates the amount of rotation required to render one or more of the teeth of the ramp 44 ineffective. By rotating the handle 52 the rack 46 is moved longitudinally to close

the gaps between certain or all of the teeth for the purpose of setting the ratchet discharge mechanism.

In order that the ramp may be moved clear of the path of the roller 43 the ramp 44 is supported at each end by an arm 58, one arm being suspended from the spindle 51 and the other arm being connected to one arm of a bell crank lever 59. The other arm of the bell crank lever 59 is connected by a link 60 to one arm of a second bell crank lever 61 the other arm of which is connected to the spindle 51. The spindles 54 and 51 carrying the sprocket wheels 53 and 56 are connected together by means of a sliding rod 62 adapted to be moved in vertical guides by means of a handle 63 thus raising directly one of the arms 58 mounted on the spindle 51 the other arm 58 being raised through the bell crank levers 61 and 59 and connecting link 60.

Thus, once the ratchet wheel 8 is set correctly the handle 63 is lifted, thus raising the ramp 44 clear of the roller 43 of the ratchet setting mechanism.

A signalling arrangement may be employed with the conveyer system whereby the approach of a tray or the like which has discharged its load is indicated. Alternatively, the signalling device may be arranged to give warning of an approach of a tray to a station or to any predetermined preceding station where it will discharge its load or give warning that a tray is about to discharge its load at the next station or at any predetermined station following the station where the signal is placed.

The signal, which may be an electric lamp to give a visual warning or a buzzer or bell to give audible warning is controlled by a switch 64, the switch arm 65 of which is controlled by a pivotally mounted ramp 66. The ramp 66 is disposed in the path of a rocking lever 67 which is normally depressed by the ramp 66 without operating the switch. When the tray carrying the load has passed a predetermined number of stations dependent upon the setting of the ratchet wheel 8 a cam ratchet 68, which in the embodiment shown in Figs. 6 and 7 is integral with the ratchet wheel 38, is brought into a position to prevent the rocking arm 67 being depressed. The ramp 66 is then moved longitudinally of the rocking arm 67 and the switch arm 65 closes the switch to light the warning lamp or close an electrical circuit containing a buzzer or bell. Naturally, the signal can be arranged to operate for any particular setting of the tray tilting mechanism depending on the relative positioning of the cam ratchet 68 and the deep tooth on the ratchet wheel 8 which operates the tilting mechanism.

It will be seen thus that three forms of ramps may be provided along the conveyor system viz: (1) Ramp 26 which engages the rocking arm 10 to actuate the tray tilting mechanism. (One of these ramps is located at every discharge station.)

(2) Ramp 66 which engages the rocking arm 67 to operate the signalling device. (A ramp 66 is located at any point where it is desired to operate the signalling device.) And

(3) The multiple ramp 44 which operates the setting mechanism for the discharge of a load at any predetermined station.

The ramps 44 are located at points along the conveyer track where it is desired to set automatically the ratchet for the discharge of a load from a tray at any predetermined following station.

In the embodiment shows in Fig. 8 the ramps 26 and 66 are carried by the same hangers.

I claim:—

1. A conveyer system comprising in combination with a conveyer track presenting a plurality of discharge stations and a series of load carriers movable along said track, ramps located adjacent said discharge stations, pawl and ratchet mechanism mounted on each of said load carriers, said pawl and ratchet mechanism operable by said ramps and load discharging means associated with each of said carriers, said load discharging means including a lever operable positively by the pawl of said pawl and ratchet mechanism on a predetermined movement of the ratchet mechanism.

2. A conveyer system comprising in combination with a conveyer track presenting a plurality of discharge stations and a series of load carriers movable along said track, ramps located adjacent said discharge stations, pawl and ratchet mechanism mounted on each of said load carriers, said pawl and ratchet mechanism operable by said ramps and means for tilting said load carriers whereby to discharge the loads of said carriers, said tilting means including a lever operable positively by the pawl of said pawl and ratchet mechanism on a predetermined movement of the ratchet mechanism.

3. A conveyer system comprising in combination a conveyer track presenting a plurality of discharge stations, a series of ramps disposed along the track and adjacent the discharge stations, a series of load carriers mounted for movement along said track, a ratchet wheel mounted on each of said carriers, a lever mounted coaxially of each ratchet wheel, an arm on each of the carriers adapted to co-operate with said ramps, a pawl carried by each of said arms adapted to engage said ratchet wheel and in one position of said ratchet wheel to engage also said lever and tilting mechanism on each of said carriers operable by said lever.

4. A conveyer system comprising in combination a conveyer track presenting a plurality of discharge stations along said track, a series of ramps disposed along the track and located adjacent the discharge stations, a series of load carriers mounted for movement along said track, a ratchet wheel with differently spaced ratchet teeth supported for rotation on each load carrier, an arm mounted on each load carrier, said arm operable by the ramps, a pawl carried by said arm for advancing the ratchet tooth by tooth, a lever masked by said ratchet wheel operable positively by the pawl when a predetermined tooth of the ratchet is engaged thereby, and tilting mechanism associated with the load carrier operable by said lever.

5. A discharge device for a load carrier of a conveyer comprising a spindle on each of said carriers, a ratchet wheel mounted on said spindle, means for adjusting the initial angular position of said spindle on the carrier and hence the initial angular position of the ratchet wheel, a movable arm mounted on said spindle, a pawl mounted on said arm for engagement with said ratchet wheel, ramps disposed along said conveyer track in the path of said arm, tilting mechanism associated with each of said carriers and a lever operatively connected to said tilting mechanism and mounted on said spindle, said lever adapted in one position of said ratchet to be engaged by said pawl to operate the tilting mechanism.

6. A discharge device for a load carrier of a conveyer comprising a spindle on each of said carriers, a ratchet wheel mounted on said spindle, means for remotely controlling the initial angular position of said spindle on the carrier and hence the initial position of the ratchet wheel, a movable arm mounted on said spindle, a pawl mounted on said arm for engagement with said ratchet wheel, ramps disposed along said conveyer track in the path of said arm, tilting mechanism associated with each of said carriers and a lever operatively connected to said tilting mechanism and mounted on said spindle, said lever adapted in one position of said ratchet to be engaged by said pawl to operate the tilting mechanism.

7. A discharge device for a load carrier of a conveyer comprising a spindle on each of said carriers, a ratchet wheel mounted on said spindle, means for remotely controlling the initial angular position of said spindle on the carrier and hence the initial position of the ratchet wheel, said means comprising a star wheel mounted on each of said spindles, a frame, a series of pins mounted in said frame, springs mounted on said pins between said frame serving to hold said pins out of engagement with said star wheel, a ramp associated with said frame, said ramp being adapted to move and depress one or more of said pins whereby to rotate said star wheel and said spindle, a movable arm mounted on said spindle, a pawl mounted on said arm for engagement with said ratchet wheel, ramps disposed along said conveyer track in the path of said arm, tilting mechanism associated with each of said carriers and a lever operatively connected to said tilting mechanism and mounted on said spindle, said lever adapted in one position of said ratchet to be engaged by said pawl to operate the tilting mechanism.

8. A discharge device for a load carrier of a conveyer comprising a spindle on each of said carriers, a ratchet wheel mounted on said spindle, a movable arm mounted on said spindle, a pawl mounted on said arm for engagement with said ratchet wheel, ramps disposed along said conveyer track in the path of said arm, tilting mechanism associated with each of said carriers, a lever operatively connected to said tilting mechanism and mounted on said spindle, said lever adapted in one position of said ratchet to be engaged by said pawl to operate the tilting mechanism and means for remotely controlling the initial angular position of said spindle on the carrier and hence the initial position of the ratchet wheel, said means comprising a second ramp disposed along the conveyer track and means mounted on each of said carriers and operable by said second ramp for altering the angular position of the ratchet mechanism independently of the first mentioned ramp.

9. A discharge device for a load carrier of a conveyer comprising a spindle on each of said carriers, a ratchet wheel mounted on said spindle, a movable arm mounted on said spindle, a pawl mounted on said arm for engagement with said ratchet wheel, ramps disposed along said conveyer track in the path of said arm, tilting mechanism associated with each of said carriers, a lever operatively connected to said tilting mechanism and mounted on said spindle, said lever adapted in one position of said ratchet to be engaged by said pawl to operate the tilting mechanism, and means for remotely controlling the initial angular position of said spindle on the carrier and

- hence the initial position of the ratchet wheel, said means comprising a second ratchet wheel mounted on said spindle, a second series of ramps disposed along the conveyer track, a link pivoted 5 on each of said load carriers, said link being adapted to engage and be depressed by each of said second series of ramps, a pawl mounted on said link, said pawl engaging and advancing said second ratchet wheel on depression of said link.
10. A discharge device for a load carrier of a conveyer comprising a spindle on each of said carriers, a ratchet wheel mounted on said spindle, means for remotely controlling the initial angular position of said spindle on the carrier and hence the initial position of the ratchet wheel, said means comprising a ramp disposed along the conveyer path, said ramp being provided with spaced teeth, a rack associated with said ramp, said rack being adapted to be moved axially of said ramp to close the gap between said teeth; a link pivoted on each of said load carriers, said link being adapted to engage and be depressed by the teeth of said ramp, a pawl mounted on said link, a second ratchet wheel for advancing said ratchet on said spindle, said second ratchet wheel being rotated by said link, means for moving said ramp out of the path of said link, a movable arm mounted on said spindle, a pawl mounted on said arm for engagement with said ratchet wheel, a series of ramps disposed along said conveyer track in the path of said arm, tilting mechanism associated with each of said carriers and a lever operatively connected to said tilting mechanism and mounted on said spindle, said lever adapted in one position of said ratchet to be engaged by said pawl to operate the tilting mechanism. 15
15. A discharge device for a load carrier of a conveyer comprising a spindle on each of said carriers, a ratchet wheel mounted on said spindle, a movable arm mounted on each of said load carriers, said second arm being adapted to be rocked when engaged by said second ramp, means for preventing rocking of said second arm in any predetermined position whereby said second ramp is moved to close said switch and give a visual warning. 20
20. A discharge device for a load carrier of a conveyer comprising a spindle on each of said carriers, a ratchet wheel mounted on said spindle, a movable arm mounted on each of said load carriers, said second arm being adapted to be rocked when engaged by said second ramp, means for preventing the rocking of said second arm in any predetermined position whereby said second ramp is moved to close said switch and give a visual warning. 25
25. A discharge device for a load carrier of a conveyer comprising a spindle on each of said carriers, a ratchet wheel mounted on said spindle, a movable arm mounted on each of said load carriers, said second arm being adapted to be rocked when engaged by said second ramp, means for preventing the rocking of said second arm in any predetermined position whereby said second ramp is moved to close said switch and give a visual warning. 30
30. A discharge device for a load carrier of a conveyer comprising a spindle on each of said carriers, a ratchet wheel mounted on said spindle, a movable arm mounted on each of said load carriers, said second arm being adapted to be rocked when engaged by said second ramp, means for preventing the rocking of said second arm in any predetermined position whereby said second ramp is moved to close said switch and give a visual warning. 35
35. A discharge device for a load carrier of a conveyer comprising a spindle on each of said carriers, a ratchet wheel mounted on said spindle, a movable arm mounted on each of said load carriers, said second arm being adapted to be rocked when engaged by said second ramp, means for preventing the rocking of said second arm in any predetermined position whereby said second ramp is moved to close said switch and give a visual warning. 40
11. A discharge device for a load carrier of a conveyer comprising a spindle on each of said carriers, a ratchet wheel mounted on said spindle, a movable arm mounted on said spindle, a pawl
